[57] **ABSTRACT**

A freezer monitor switch comprising an elongate, hollow tube which is closed at one end and has its other end equipped with a closure. A pair of current carrying leads communicate with the interior of the tube through the closure and terminate interiorly in a pair of spaced contacts. A small quantity of water or other freezable liquid and a slidably, electrically conductive element are retained interiorly of the tube. The switch initially mounts within the freezer with the open end facing upwardly and with the closed end positioned downwardly until such time as the water freezes and secures the conductive element at the closed end of the tube. The switch is then rotated through 180° within the freezer and is positioned with the frozen in place conductive elements above the contacts. Should the freezer fail for any reason, the water will melt to thereby release the conductive element which falls by gravity and bridges the space between the conductive contacts. Preferably, the electrical leads and contacts form parts of an alarm circuit which will be energized upon contact of the conductive element with the pair of spaced contacts.

BACKGROUND OF THE INVENTION

The present invention relates generally to the field of warning devices, and more particularly, is directed to a switch and alarm system suitable to signal operational failure of a freezer.

The use of freezers of both the residential type and the commercial type has become increasingly popular and more and different types of food are being stored in frozen condition both in supermarkets and in the home. The frozen food industry has grown rapidly in recent years and there is every indication that its popularity will continue to increase at an undiminished rate. By employing the techniques developed in the frozen food industry, foods can now be prepared at the processing plant and delivered to the table in a manner which renders the food more palatable, more wholesome and fresher than comparable foods in unfrozen condition.

In order to maintain the wholesomeness of frozen foods, it is important that the food remain frozen at all times after the initial freezing at the packaging plant until such time as the food is prepared for serving. To this end, commercial and residential freezers are widely employed and have proved generally satisfactory to maintain the frozen condition of the food. However, experience has shown that freezers, just as any other type of mechanical equipment are subject to unexpected failures due to any number of mechanical or electrical reasons. In those establishments wherein persons are normally actively engaged in the vicinity of the freezer, such freezer failure is usually rapidly observed and such measures as may be necessary to preserve the integrity of the frozen food can be taken. However, in many instances, freezers are located in relatively deserted areas and so a failure could go undetected for a relatively long period of time. In other instances, freezer failure could occur during the evening hours so that such a malfunction would not be normally observed until the following morning. Under such conditions, the frozen food could defrost and even spoil to thereby negate any advantage previously obtained by maintaining the food in frozen condition.

Prior workers in the art have attempted to develop some type of warning device to visually indicate when the desired temperature conditions within a freezer are not maintained. The devices disclosed in U.S. Pat. Nos. 3,518,961, 3,618,558 and 3,461,834 are exemplary of prior art warning devices. These devices have generally proved unsatisfactory in that they did not also provide for a reliable, easily installed audible alarm system.

SUMMARY OF THE INVENTION

The present invention relates to a novel freezer monitor switch, and more particularly, is directed to a tubular type of switch member having a freezable liquid therein which acts to retain a conductive element in spaced relationship above a pair of alarm circuit contacts.

The present invention includes a generally hollow tubular member which is closed at one end and has its second end closed by a closure such as a stopper which carries a pair of electrical conductors. The conductors

terminate interiorly of the tubular member in a pair of spaced contacts. Within the tubular member is retained a small quantity of freezable liquid such as water and a movable switch part which may be in the form of a conductive element which is configured to be slidable within the interior of the tubular member.

A spring bracket retains the freezer monitor switch within a freezing compartment and initially, the freezer monitor switch is positioned with the closed end facing downwardly and with the conductor equipped end facing upwardly. The conductive element falls by gravity within the tubular member and is associated with the freezable liquid at the closed end. By maintaining the switch in this position within the freezing compartment until the liquid freezes, the conductive element is then secured at the closed end of the freezer monitor switch. After the conductive element has been so frozen, the switch is then rotated through 180° relative to the bracket within the freezer compartment so that the closed end positions upwardly with the frozen water and the entrapped conductive element retained in vertical alignment above the spaced contacts. An electrical circuit preferably containing audible alarm and perhaps also a visual alarm connects to the conductors and to a conventional source of electrical energy, such as a battery or a conventional source of electrical energy, such as a battery or a conventional duplex receptacle. Under normal conditions, no current is open between the pair of spaced contacts which are positioned within the tubular member. Should freezer failure occur, the ice which had been frozen within the tubular member will melt and thereby release the conductive element. Once released, the conductive element falls by gravity within the tubular member and falls directly upon the spaced contacts. The conductive element bridges the opening across the spaced contacts to thereby complete the electrical circuit and allow the flow of current therein. Current flow within the electrical circuit will then activate the audible or visible alarm signal to alert interested parties to the fact that the freezer had malfunctioned. Once alerted, proper corrective action can be taken in due time to prevent spoilage of the frozen food.

It is therefore an object of the present invention to provide an improved freezer monitor switch of the type set forth.

It is another object of the present invention to provide a novel freezer monitor switch which incorporates a tubular body and an electrically conductive element slidably within the tubular body, said conductive element being retained in a circuit open position when the freezer is properly operated and said element falling by gravity to a circuit closed position to activate an alarm signal upon failure of the freezer.

It is another object of the present invention to provide a novel freezer monitor switch which incorporates a hollow tubular body having one closed end and one open end, the said open end being equipped with a closure and a pair of electrical conductors, the said conductors terminating interiorly of the tubular body to form a pair of switch contacts and electrically conductive means retained within the tubular member and arranged to engage the contacts upon failure of the freezer mechanism.

It is another object of the present invention to provide a novel freezer monitor switch that is inexpensive

in manufacture, automatic in operation and trouble free when in use.

Other objects and a fuller understanding of the invention will be had by referring to the following description and claims of a preferred embodiment thereof, taken in conjunction with the accompanying drawings wherein like reference characters refer to similar parts throughout the several views and in which:

BRIEF DESCRIPTION OF THE DRAWINGS

FIG. 1 is a perspective view of a refrigerating device containing a freezer compartment, partially broken away to show an interior mounted freezer monitor switch.

FIG. 2 is an enlarged, perspective view of a freezer monitor switch constructed in accordance with the present invention.

FIG. 3 is a side elevational view of the freezer monitor switch of FIG. 2 in a first position, partially broken away to expose details of interior construction.

FIG. 4 is a view similar to FIG. 3 showing the freezer monitor switch in second position after the conductive element has been frozen in position and partially broken away to expose details of interior construction.

FIG. 5 is a view similar to FIG. 4 showing the conductive element in circuit closing position and partially broken away to expose details of interior construction.

FIG. 6 is a schematic electrical diagram of the alarm circuit.

FIG. 7 is an enlarged, perspective view of a modified conductive element.

FIG. 8 is an enlarged, perspective view of a second modified conductive element.

FIG. 9 is an enlarged, perspective view of a third modified conductive element.

SUMMARY OF THE PREFERRED EMBODIMENT OF THE INVENTION

Although specific terms are used in the following description for the sake of clarity, these terms are intended to refer only to the particular structure of our invention selected for illustration in the drawings and are not intended to define or limit the scope of the invention.

Referring now to the drawings, we show in FIGS. 2-5 a freezer monitor switch generally designated 10 which preferably is fabricated with an elongated, hollow body 12 having a closed end 14 and an open end 16. The hollow body 12 contains a small quantity of a freezable liquid 18, such as water, which serves to retain the conductive element 20 at the closed end 14 of the hollow body 12 when in use as hereinafter more fully set forth.

A water tight closure 22, which may be fabricated of rubber, plastic or other waterproof and electrically non-conductive material, is a force fit into the open end 16 of the hollow body 12 to provide a closure therefore. A pair of conductors 24, 26 insert through the closure 22 in a conventional, leakproof manner and terminate within the hollow body interior space 28 in a pair of similar, spaced, electrical contacts 30, 32. The electrical contacts 30, 32 project interiorly of the interior surface of the closure 22 a sufficient distance to receive the conductive element 20 in an electrically conductive engagement without interference from the closure material itself.

As best seen in FIGS. 3, 4 and 5, the conductive element 20 includes an elongated body 36 and an integral

contact head 38 which is sized to readily slide within the interior space 28 defined within the hollow body 12. The elongated nature of the conductive element body 36 serves to orient the longitudinal axis of the conductive element 20 with the longitudinal axis of the hollow body 12 to prevent binding therein and to assure positive electrical engagement between the contact head 38 and the pair of spaced electrical contacts 30, 32 when the switch is activated. In the embodiment illustrated, the head 38 is shown of relatively discoid configuration to ride within the cylindrical configuration of the hollow body 12.

As seen in FIGS. 1 and 2, a mounting bracket 44 mounts within the freezer compartment 46 and is provided with a pair of outwardly projecting spring arms 48, 50. The spring arms are provided with sufficient spring tension to readily receive and hold the hollow body 12 when the freezer monitor switch is gently pushed into the open space 52 which is defined between the spring arms 48, 50.

As illustrated in FIG. 6, the electrical conductors 24, 26 form part of an electrical series circuit 54 including the pair of terminals 56, 58 which are connected in well known manner to a source of electrical energy (not shown) such as a conventional battery or a conventional duplex receptacle. An alarm bell 60 connects in series in the circuit 54 in a manner to be energized when current flows within the circuit. As illustrated, the freezer monitor switch 10 serves as the circuit switch and accordingly when the conductive element 20 is maintained out of contact with the electrical contacts 30, 32, such as by the function of the ice 62 (FIG. 4) which is produced by freezing the water 18, the circuit 54 will be open and no electrical current will flow. Should the ice 62 melt to thereby release the conductive element 20, the switch 10 will close to thereby permit the flow of electrical current through the circuit 54 to activate the bell 60 or any other type of conventional alarm device which is wired into the circuit.

In order to operate the freezer monitor switch of the present invention, the mounting bracket 44 is positioned within the freezer compartment 46 in a convenient location to permit access thereto. Then the freezer monitor switch is placed interiorly of the freezer compartment 46 by associating it with the mounting bracket 44 and by orienting the switch with the closed end 14 facing downwardly as in FIGS. 2 and 3. The freezer monitor switch 10 is maintained within the freezer compartment a sufficient length of time to freeze the water 18 to ice 62 to thereby entrap the conductive element 20 in a position near the closed end 14. Upon freezing of the water 18, the freezer monitor switch 10 is then removed from its association with the mounting bracket 44, is rotated through 180° and then reassociated with the mounting bracket within the freezer compartment 46. The freezing atmosphere within the compartment 46 serves to maintain the ice 62 in frozen condition so that the conductive element 20 remains associated at the closed end 14 of the hollow body 12 as illustrated in FIG. 4. The terminals 56, 58 of the electrical circuit 54 are then associated with a source of electrical energy (not shown) to power the circuit 54. In this condition, the freezer monitor switch 10 is set to detect any malfunction in the freezer operation of sufficient magnitude to cause loss of the freezing atmosphere within the compartments 46 to melt the ice 62. Should the freezer fail and the ice 62 melt, the con-

ductive element 20 which was previously frozen in position associated with the closed end 14 by action of the ice 62 is then free to fall within the interior space 28 defined within the hollow body 12 until the conductive element 20 contacts the pair of spaced electrical contacts 30, 32 to thereby complete the electrical circuit 54 which activates the alarm device 60.

Referring now to FIG. 7, we show a modified conductive element 20' wherein the element body 36 is provided with a plurality of radially outwardly directed pins 42 which are in spaced relation to the contact head 38. The pins terminate outwardly at the projected perimeter of the contact head 38 to readily slide within the hollow body 12. The spaced relationship between the pins 42 and the contact head 38 serves to assure longitudinal alignment of the element body 36 within the hollow body 12 at all times. Similarly, in FIG. 8, a second discoid element 38'' is provided in spaced relation from the contact head 38 to assure longitudinal alignment of the second modified conductive element 20''.

Referring to FIG. 9, a third modified conductive element 20''' is illustrated wherein the element body 36''' is formed to cylindrical configuration of diameter slightly smaller than the interior diameter of the hollow body 12 to thereby encourage longitudinal movement without the possibility of longitudinal alignment. In this modification, the contact head 38''' is simply the bottom face of the conductive cylinder.

Although we have described the present invention with reference to the particular embodiments herein set forth, it is understood that the present disclosure has been made only by way of example and that numerous changes in the details of construction may be resorted to without departing from the spirit and scope of the invention. Thus, the scope of the invention should not be limited by the foregoing specification, but rather only by the scope of the claims appended hereto.

We claim:

1. In a freezer monitor switch positioned within a 40 freezer, the combination of
  - A. a hollow body having one closed end and one closed contact containing end;
  - B. an electrically conductive element positioned within the body,
    1. the conductive element comprising an elongated body and a contact head, the contact head having a diameter to readily slide within the hollow body,
    2. said element being movable from a first position to a second position, the first position being

- above the second position;
- C. a quantity of freezable liquid contained within the body;
  - a. said liquid being frozen to a solid state by operation of the freezer,
  - b. the said liquid when in the solid state maintaining the element in its first position,
  - c. the said liquid melting to the liquid state upon freezer failure to release the element,
  - d. the element falling by gravity from the first position to the second position upon freezer failure;
  - D. a pair of spaced electrical contacts positioned at the contact containing end,
    1. the contacts extending into the interior space,
    2. the said element being positioned at the closed end and spaced from the contacts when in the first position,
    3. the said element contacting both of the electrical contacts and forming an electrically conductive path therebetween when the element is moved to its said second position,
  - E. a bracket mounted interiorly of the freezer,
    1. said hollow body being removably mounted on the bracket,
    2. the hollow body being initially mounted within the freezer with the closed end down and the contact containing end up,
    3. the said freezable liquid and conductive element initially falling to the said closed end and the action of the freezer freezing the liquid and entrapping the conductive element at the closed end,
    4. the hollow body being then removed from the bracket and being rotated through 180° within the freezer after the liquid is frozen to position the closed end vertically above the contact containing end and being remounted on the bracket.
  2. The invention of claim 1 wherein the conductive element includes means to maintain the conductive element in axial alignment within the hollow body.
  3. The invention of claim 2 wherein the means comprise a plurality of pins which extend outwardly from the elongated body, said pins being spaced from the contact head.
  4. The invention of claim 2 wherein the means comprise a disc connected to the elongated body, said disc being spaced from the contact head.
  5. The invention of claim 1 wherein the conductive element comprises a body of cylindrical configuration, said body having a diameter slightly smaller than the 50 interior diameter of the hollow body.
